UNITED STATES PATENT OFFICE

121,340

DESIGN FOR A SHOE

August I. Scherer, Elm Grove, Wis.

Application February 6, 1939, Serial No. 82,807

Term of patent 3½ years

To all whom it may concern:

Be it known that I, August I. Scherer, a citizen of the United States, residing at Elm Grove, in the county of Waukesha and State of Wisconsin, have invented a new, original, and ornamental Design for a Shoe, of which the following is a specification, reference being had to the accompanying drawing, forming a part thereof, and in which:

Figure 1 is a view in side elevation of a shoe showing my new design; and

Figure 2 is a top plan view thereof.

The characterizing features of my design reside in the shoe shown, having two rows of relatively

long loops on the side of the shoe extending from the toe rearwardly, the upper row lying over the top of the instep, the lower row extending along the sole line and terminating at the beginning of the instep, said instep portion including relatively short interlaced loops merging into relatively long horizontal loops substantially covering the heel portion from the sole line to the counter line.

I claim:

The ornamental design for a shoe, as shown and described.

AUGUST I. SCHERER.
